(57) **CLAIM**

The ornamental design for a stand for consumer paper products, as shown and described.

DESCRIPTION

FIG. 1 is a perspective view of a stand embodying our new design;

FIG. 2 is a front view of the stand shown in FIG. 1;

FIG. 3 is a back view of the stand shown in FIG. 1;

FIG. 4 is a side view of a first side of the stand shown in FIG. 1;

FIG. 5 is a side view of a second side of the stand shown in FIG. 1;

FIG. 6 is a top view of the stand shown in FIG. 1; and,
FIG. 7 is a bottom view of the stand shown in FIG. 1.

The broken lines in the drawings represent unclaimed environmental subject matter illustrating the design in use and form no part of the claim.
